[57] CLAIM

The ornamental design for a milk bottle crate, substantially as shown and described.

DESCRIPTION

FIG. 1 is a top plan view of a milk bottle crate showing my new design;
 FIG. 2 is a side elevational view of the milk bottle crate;
 FIG. 3 is an end elevational view of the milk bottle crate;
 FIG. 4 is a bottom plan view of the milk bottle crate;
 FIG. 5 is a sectional view taken substantially along the line 5—5 of FIG. 2;
 FIG. 6 is a sectional view taken substantially along the line 6—6 of FIG. 3;
 FIG. 7 is an enlarged fragmentary sectional view taken substantially along the line 7—7 of FIG. 2;
 FIG. 8 is a top plan view of a milk bottle crate showing a modified form of my new design.
 FIG. 9 is a side elevational view of the milk bottle crate shown in FIG. 8; and
 FIG. 10 is a bottom plan view of the milk bottle crate shown in FIG. 8.
 The two ends of the milk bottle crate shown in FIG. 1 are identical. The two sides of the milk bottle crate shown in FIG. 1 are identical. All four sides of the milk bottle crate shown in FIG. 8 are identical. The milk bottle crate shown in FIG. 8 has the same appearance in cross section as is indicated by FIGS. 5 and 6 of the milk bottle crate shown in FIG. 1.
